UNITED STATES PATENT OFFICE

EMIL F. PETERSON AND SVEN A. PETERSON, OF BROOKLYN, NEW YORK

HEEL BRACE OR SUPPORT

Application filed July 2, 1928. Serial No. 289,830.

This invention relates to heel braces or supports for shoes having high heels, and especially to such braces as are applied to heels in order to prevent their accidental removal or loss.

The main object of our invention is to reinforce high heels on women's shoes in order to give them greater strength and add durability to such shoes.

10 Another object is to provide a support of the character indicated which is entirely unobtrusive and which does not appreciably increase the weight or size of a shoe to which it is applied.

15 A further object is to provide a heel support which may be stamped and formed from sheet metal, which is inexpensive, and which is readily applied.

Further objects and advantages of our invention will appear hereinafter as this specification proceeds.

In the accompanying drawings,

Fig. 1 is a view of a woman's shoe having the invention applied thereto in the form of 25 a stamped metal support.

Fig. 2 is another view of the same shoe and support to more clearly show the proper position of the invention relatively to the shoe.

Fig. 3 is a view from one side of a stamped 30 plate embodying our invention.

Fig. 4 is another view of the same in a different position.

Fig. 5 is a further view of the same when turned with the left end of Fig. 4 toward 35 the observer.

Fig. 6 is a similar view to Fig. 5 when the left end of the support is in line with the eye to show its curvature.

Throughout the views, the same reference 40 numerals indicate the same or duplicate parts.

It is a matter of frequent occurrence that high heels have a tendency to bend or break off women's shoes, especially when subject 45 to sudden or heavy strains and shocks. If the shoe 1 having a sole 2 and a heel 3 is subjected to violent backward shocks or strains so that the heel must bear the brunt of the same, the height of the heel from the rear edge 12 to the junction between the heel

and the shoe upper will in great measure constitute a leverage tending to fulcrum at the section indicated at 11.

If the strain is great enough, the sole may bend or break off at that point, providing 55 the heel is strongly attached to the shoe, but more often, the result is that the heel parts from the shoe altogether.

It is now proposed to form a supporting plate generally indicated by 10, into an arcuate member 4 which is reinforced for rigidity by a relief rib 9, the latter being pressed up as at 14 from the main portion 4, and then secure this arcuate member at the extremities to the heel 3 and sole 2 of the shoe. In order to adapt this plate for such attachment, one end is formed into an enlarged tongue 8 to be secured by rivets, nails or screws 7 to the inner face 13 of the heel, while the other end is broadened into a transversely curved portion 5 to conform with the usual convex form of the sole under the instep, and is there attached by rivets, nails or screws as at 6.

It is obvious that the diagonal strain 71 through the heel originating at the rear edge 12 and concentrating at 11 is now taken up by our new support plate which distributes the strain from about the middle of the heel to a point well forward in the sole under the 76 instep, and very greatly strengthens the attachment and position of the heel on the shoe.

The support plate may be made of any metal or useful material which may serve for the described purpose, but sheet steel is preferred.

Having now described our invention, we claim:

1. A unitary heel plate including the combination with a main elongated section which is intermediately ribbed along its length, the rib structure being spaced within the edges so as to provide relatively flat edges on both sides thereof, a broadened section upon each end of said main section, and means adapting said plate to conform to the shape of the heel and shank of the shoe to which said plate may be attached.

2. In a heel support plate of unitary structure for attachment to the forward face of

the heel of a shoe and to the underside of the shank portion thereof, a bent main portion provided with reinforcing and stiffening means spaced within the edges thereof, a broadened section disposed upon each end of said main portion, and means upon said plate adapting one broadened end section thereof to conform with the form of said shoe including a transversely arcuate form of said end section.

5 In testimony whereof, we have signed our names to this specification this 30th day of June, 1928.

15 EMIL F. PETERSON.
